CLOSURE CAP FOR GAS TANKS OR THE LIKE

Eugene Kawecki, Detroit, Mich., assignor to Sturdevant Manufacturing Corporation, Detroit, Mich., a corporation of Michigan

Filed Nov. 23, 1959, Ser. No. 58,424

Term of patent 14 years

(Cl. D58—26)

FIG. 1

FIG. 2

FIG. 3

FIG. 4

Fig. 1 is a top plan view of a closure cap for gas tanks or the like, showing my new design;

Fig. 2 is a side elevational view thereof;

Fig. 3 is a perspective view thereof; and

Fig. 4 is an elevational view of the left side of Fig. 2.

I claim:

The ornamental design for a closure cap for gas tanks or the like, substantially as shown.
